(57) **CLAIM**

The ornamental design for an electric scooter, as shown and described.

DESCRIPTION

FIG. 1 is a front perspective view of the electric scooter of the present invention;

FIG. 2 is a front view of the invention of FIG. 1;

FIG. 3 is a rear view of the invention of FIG. 1;

FIG. 4 is a side view of the invention of FIG. 1, as seen from the left side of FIG. 2;

FIG. 5 is a side view of the invention of FIG. 1, as seen from the right side of FIG. 2;

FIG. 6 is a top plan view in elevation of the invention of FIG. 1; and,

FIG. 7 is a bottom plan view of the invention of FIG. 1. The broken lines are for the purpose of illustrating portions of the article that form no part of the claim.
